UNITED STATES PATENT OFFICE.

THOMAS B. BROWN, OF MOUNT VERNON, INDIANA.

MATCH-SAFE.

SPECIFICATION forming part of Letters Patent No. 289,500, dated December 4, 1883,

Application filed August 31, 1883. (No model.)

To all whom it may concern:

Be it known that I, THOMAS B. BROWN, a citizen of the United States, residing at Mount Vernon, in the county of Posey and State of Indiana, have invented certain new and useful Improvements in Match-Safes, of which the following is a specification, reference being had thereto to the accompanying drawings.

This invention relates to improvements in match-safes; and it has for its object to utilize the handles of domestic utensils for that purpose. This object is attained by the device illustrated in the accompanying drawings, forming a part of this specification, in which—

15 Figure 1 is an elevation. Fig. 2 is a section. Fig. 3 is a transverse section. Fig. 4 is a modification.

The letter A indicates the match-safe, forming a part of the handle of a bucket or pail. 20 B is the bail. C is the cover, hinged at D, and lined on the inside with sand-paper F, and

provided with a catch, E, to hold it down when shut.

The safe may be made of any suitable material—such as sheet metal or wood—and the 25 cover C may be lined with any abrasive material, F, adapted to strike matches upon.

G is a spring. (Shown in Fig. 4.)

Having described my invention, what I desire to secure by Letters Patent and to claim 30 is—

In a match-safe, the part A, having cover C, lined with abrasive material, hinged at D, and provided with catch E, in combination with the bail B, as described, and for the purposes 35 set forth.

In testimony whereof I affix my signature in presence of two witnesses.

THOMAS B. BROWN.

Witnesses:

W. S. SPITMER,

GEORGE SHELHORN.
